AUTOMATIC BOILER CLEANER

Abraham A. Stutsman, San Jose, Calif.

Application September 22, 1933, Serial No. 690,617

3 Claims. (Cl. 122—389)

The present invention relates to boiler cleaners, and more particularly for that type adapted to be installed in boilers for automatically collecting scale, mud or other foreign accumulations which are carried into and which form within the boiler.

Another object of the present invention is to provide a cleaner of this type which not only collects the foreign substances in the boiler water but which also admits of the removing of the accumulations by blowing off so that the solid and other foreign matter may be removed from time to time according to the rate of accumulation.

The invention also aims to provide a device of this character which does not require any modification or change in the boiler structure but which may be quickly and easily installed therein and which has no moving parts and which effects separation of the solids from the boiler water by precipitation and also by settling.

A still further object of the invention is to provide a boiler cleaner having a feed water section adapted to receive and heat the incoming water to cause precipitation of the solids in the feed water so that the feed water will have precipitated from it the solids before the feed water enters the boiler water.

The invention also has for an object to provide a cleaner of this type with a settling section adapted to be located in the boiler at a point to receive circulation therethrough of the water at its most turbulent point in the boiler so as to entrap the scale and sludge from the greatest point of vantage.

With the foregoing and other objects in view, the invention will be more fully described herein-after, and will be more particularly pointed out in the claims appended hereto.

In the drawing, wherein like symbols refer to like or corresponding parts throughout the several views,

Figure 1 is a side elevation partly broken away of one type of boiler showing the present invention applied thereto.

Figure 2 is a transverse section taken through the same substantially on the line 2—2 of Figure 1.

Figure 3 is a top plan view of the boiler cleaner, a steam pipe of the boiler being shown in relation thereto, and

Figure 4 is a fragmentary enlarged transverse section taken through the boiler with the cleaner therein on substantially the line 4—4 of Figure 1.

Referring now to the drawing, 10 designates a boiler of conventional type and which may be provided intermediate its ends with a steam dome 11 from which leads in the usual manner a steam

pipe 12, the same extending forwardly within the top of the boiler 10. The rear portion of the boiler houses a fire box 13 defined at its top by a crown sheet 14 and at its forward end by a flue sheet 15. A feed water pipe 16 is disposed at the forward end of the boiler 10 and is adapted to supply water to the boiler in the usual manner. The cleaner of the present invention embodies a forward section and a rear section. The forward section comprises one or more troughs 17 open 10 at its top and which is rounded or otherwise converged at its bottom. The forward end of the trough is provided near its upper edge with a feed water receiving pan 18 relatively shallow and into which opens the down-turned end of the feed water pipe 16, as shown in Figure 1. The pan 18 is preferably of the width of the trough 17 and opens into the upper edge portion thereof so as to spread the feed water over a relatively large surface area in the trough and to break 20 the jet or stream action of the water as it is forced into the boiler.

The trough 17 is suspended in the upper portion of the boiler 10 so that a substantial upper portion of the trough is above the water level 25 19 in the boiler. The feed water flows gradually from the forward to the rear end of the trough 17 and spills over the rear end of the trough into the body of boiler water. Preferably the rear wall 20 of the trough 17 is slightly shorter than 30 the adjacent walls so as to confine the rearwardly flowing feed water in the trough throughout the length of the latter and to admit of the spilling over of the water from the rear end of the trough only. To offset the undue disturbance 35 or splashing of the water traveling lengthwise in the trough 17, the trough may be provided with one or more transverse baffle plates 21 which extend downwardly from the upper edge of the trough a suitable distance and which are preferably perforated so as not to impede to any appreciable extent the continuous and undisturbed flow of the feed water through the trough. This will prevent the splashing of the feed water particularly when the boiler 10 is of the locomotive type and the latter is subjected to quick starting or stopping.

For the purpose of cleaning out the accumulated sludge from the bottom of the trough incident to precipitation from the incoming feed 50 water, due to the sudden subjection of the water to the relatively high temperature in the top of the boiler, the trough 17 is provided with a blow-off pipe 22 which leads to the exterior of the boiler and is under control of a suitable blow-off 55

valve 23. This pipe 22 is provided with a branch pipe 24 which extends lengthwise through the trough 17 adjacent the bottom thereof and which is provided with a suitable number of openings or perforations 25 facing downwardly toward the bottom of the trough 17 so that when the valve 23 is open the accumulated sludge in the trough will be drawn and discharged through the blow-off pipe 22.

10 The one or more troughs 17 of the front section may be supported in the boiler in any suitable manner and in the present instance the trough 17 is shown as being suspended in a suitable number of longitudinally spaced apart hanger straps 26 and these straps 26 are preferably arranged in pairs at the outer and inner sides of the trough 17, as shown in Figure 4, so as to not only support the weight of the trough but to hold the latter from rising when the buoyancy of the surrounding boiler water takes effect, caused by the blowing out of the water from the trough. These hanger straps 26 may be secured to the top of the boiler 10 as shown, or any other suitable means may be resorted to for effecting the suspension of the trough 17.

15 The rear section of the boiler cleaner comprises one or more troughs 27 which may be relatively short and which are located to extend rearwardly from beneath the dome 11 and terminate near the juncture of the crown and flue sheets 14 and 15, as shown in Figure 1. Each trough 27 is preferably rounded or converged at its bottom and is provided with perforated opposite end walls 28 so that the boiler water may circulate lengthwise through the troughs 27 from end to end thereof. The troughs 27 are preferably located in a plane slightly below that of the front section trough 17 so that one or more troughs 27 may lie well within the water circuit 20 to receive the sludge and other accumulations which may be carried in the water and which accumulate to the greatest extent adjacent the crown sheet. The perforations in the end walls 28 are of a sufficient size to admit the sludge or solid matter in the water so that this solid matter may settle in the quiescent zone of the members 27.

25 The troughs 27 are suspended in hangers 29 of any suitable type which may be secured to the inner side of the boiler 10, or any other suitable suspension means may be resorted to. Each trough 27 is provided adjacent its bottom with a longitudinally extending branch pipe 30 having perforations 31 in its lower side and which opens into a header 32 extending across the forward ends of the troughs 27. The header 32 is connected by a rearwardly closing check valve 33 with a blow-off pipe 22 at a point inwardly of the front branch pipe 24 so that the water from the front trough 17 cannot flow backwardly through the branch pipe 24 into the header 32 or rear trough branch pipes 31. Of course, the blow-off pipe 22 is shown in the present instance as comprising a single unit with a single valve 23 therein, but it is understood that any other suitable flow-off structure may be resorted to if desired.

30 It will be noted that the perforated opposite end walls 28 of the rear troughs 27 have their perforations extending downwardly but approximately one-half the depth of the end walls so as to maintain a quiescent zone in the bottom of each trough 27 for collecting the sludge and other solids from the water and entrapping the same.

35 The operation of the forward trough section of the pipe has been above explained, and the boiler

water circulating about the fire box rises across the crown sheet 14 and, when the steam outlet is open there is naturally a strong current of the water and steam flowing from the forward end of the crown sheet 14 to the point of exit of the steam.

40 The rear section 27 is therefore located in the path of this particular stream so as to be immersed in the boiler water at the point of greatest turbulence and at which point the sludge, scale or other accumulations are naturally carried. The one or more troughs 27 thus lie in the path of circulation of this turbulent boiler water and entrap in a quiet zone, in the bottom of the trough 27, the circulating water so that the sludge and other accumulations may settle to the bottom of the trough 27 and be subsequently blown off through the branch pipes 31, header 32 and the blow-off pipe 22. This device therefore offsets all foaming and priming of the boiler so that the boiler water will not be carried off through the steam exit.

45 It is obvious that various changes and modifications may be made in the details of construction and design of the above specifically described embodiment of this invention without departing from the spirit thereof, such changes and modifications being restricted only by the scope of the following claims:—

50 What is claimed is:—

1. In combination with a boiler having a crown sheet and a steam outlet spaced from the crown sheet, a boiler water cleaner and blow out means comprising a trough having perforate ends and disposed between the inner end of the crown sheet and the outlet, the ends of the trough being perforate adjacent the upper portion thereof whereby water may continuously flow through the trough and being imperforate adjacent the lower portion thereof to form a sediment trap, means for supporting said trough between the crown sheet and the outlet in a position at substantially the normal level of the water and at a point relative to the crown sheet whereby the forwardly moving and crown sheet agitated water will pass through said perforate ends, a pipe disposed adjacent the bottom of the trough and having downwardly facing openings, and an outlet pipe connected to said first pipe.

55 2. In combination with a boiler having a crown sheet and a steam outlet spaced from the crown sheet, a combined cleaning means and blow out means, said cleaning and blow out means comprising a boiler water cleaning means and a fresh water cleaning means, and blow out means connected to said boiler water cleaning means and said fresh water cleaning means, said boiler water cleaning means comprising a trough disposed between the inner end of the crown sheet and said outlet and provided with perforate ends to permit the free passage of water through the trough at the level of the water, the ends of the trough being perforate adjacent the upper portion thereof whereby water may continuously flow through the trough and being imperforate adjacent the lower portion thereof to form a sediment trap, means for supporting said trough at the normal level of the water and between the crown sheet and the outlet, a blow out header disposed between said boiler water cleaning means and said fresh water cleaning means, and a perforate pipe section in each of said cleaning means and connected to said header.

60 3. In combination with a boiler having a crown sheet and a steam outlet spaced from the crown

sheet, a boiler water cleaner and blow out means comprising a trough having ends perforated for a portion of the distance thereof downwardly from the top whereby to permit water to freely pass 5 through the upper portion of the trough, means for supporting said trough between the inner end of the crown sheet and the outlet in a position at substantially the normal level of the water whereby the water agitated by the crown sheet 10 and moving forwardly therefrom will pass

through the perforations of said ends, the ends of the trough being perforate adjacent the upper portion thereof whereby water may continuously flow through the trough and being imperforate adjacent the lower portion thereof to form a sediment trap, a pipe disposed in trough below the perforations of the ends and having downwardly facing openings, and an outlet pipe connected to said first pipe.
